UNITED STATES PATENT OFFICE.

JAMES E. DOYLE, OF CLEVELAND, OHIO.

SHEET-DELIVERY DEVICE.

Original application filed August 20, 1920, Serial No. 404,931. Divided and this application filed September 26, 1921. Serial No. 503,218.

To all whom it may concern:

Be it known that I, JAMES E. DOYLE, a citizen of the United States, residing at 5718 Whittier Ave., Cleveland, in the State 5 of Ohio and Cuyahoga County, have invented a new and useful Improvement in Sheet-Delivery Devices, of which the following is a specification, the principle of the invention being herein explained and the 10 best mode in which I have contemplated applying that principle, so as to distinguish it from other inventions.

My invention deals with a contrivance adapted to be used in conjunction with a 15 machine upon which a sheet or sheets are to be conveyed. The drawings exemplify the application of my invention to a printing press provided with a heater as shown described and claimed in my copending application filed August 20, 1920 Serial No. 20 404,931 from which this application has been divided.

The general object of my invention is to facilitate the delivery of printed sheets and 25 to insure smooth and regular delivery thereof. Particular objects of my invention are:

1. The provision of devices at the place of delivery or release of a sheet from a conveyer and somewhat elevated relative to the 30 part of the conveyer which is so positioned as to be earlier passed over by the moving sheet. Practice has demonstrated that some control should be had of the front edge of a paper sheet at the moment it is about to 35 be delivered and stacked, in order to avoid a curling of the sheets and consequent likelihood of creasing, folding or entanglement. Such an undesirable result was not only apt to occur owing to the speed of 40 travel of the sheet, but also because if the fly sticks were not properly adjusted according to the size of the sheet the latter was not uniformly supported along its front edge. It is true, that the fly sticks at the 45 delivery end of a printing press have heretofore been made adjustable, but when the fly sticks were adjusted the necessary stop fingers were also. This was a disadvantage because the spacing of the fly sticks need 50 not and should not in every instance determine the spacing of the stop fingers. Accordingly I have provided for an adjustment of the fly sticks irrespective of the stop fingers.

55 2. I have also discovered that a retarda-

tion of the rear edge of a sheet has frequently occurred and that such action has occasionally resulted in a disalignment and subsequent improper delivery of the sheet. The action appeared to be in the nature of 60 a back draft or suction force. To remedy this I have supplied an elevated surface over which the sheets move prior to reaching the heater and then perforate such surface so as to counteract the tendency just referred to. 65

Adverting to the drawings:

Figure I is a diagrammatic view in part elevation and part section showing my invention associated with a cylinder press.

Figure II is an enlarged plan view on line 70 II-II of Figure I.

Figure III is a still further enlarged (full size) section on line III-III of Figure II.

Only cursory mention will be made of the necessary supporting parts and a few others 75 which aid in making clear the relative position of the elements of my invention.

So much of the main frame of a printing press as is shown in outline I have designated by the reference numeral 1. A further 80 portion of the frame is seen to overhang the first mentioned portion adjacent the cylinder 2. The platen 3 is seen somewhat below and superimposed upon it a number of inking rolls 4 are visible. Rotatably 85 mounted upon the over-hanging portion of the frame and removed forwardly therefrom are a pair of rollers 5 and 6 respectively. These rollers actuate the conventional type of belt conveyer 7, the upper 90 portion of which is designed to travel in a direction away from the cylinder. Positioned somewhat farther beyond and in the direction of travel of the conveyer 7 is a deposit table 8. The upper surface of this 95 table is provided near its outer edge with an abutting rail 9. Disposed above the table 8 and inclined upwardly toward the cylinder are a pair of lateral tracks 10 the purpose of which will be hereinafter explained.

A device whose function consists in carrying paper sheets forwardly beyond the location of the roller 6 will now be described. Generally speaking, it involves a traveling 105 carriage provided with a pair of linked arms capable of reciprocating it when actuated in a manner not shown since common to the art. One arm 11 is pivotally mounted to the frame at 12. The free extremity of the arm 110

11 articulates through the medium of a pivot pin 13 with the second arm 14, and the extremity of this arm articulates in a similar manner through the medium of a pin 15 with 5 the carriage 16. The carriage 16 involves in its construction forwardly and rearwardly disposed rollers 17 which are adapted to travel upon the tracks 10. The carriage 16 is provided with a depending bracket 20 10 which supports a rod 21 extending between the members 10. Secured along the rearward portion of the rod 21 and fixedly maintained in an inclined position are a plurality of aligned sticks 22. These sticks constitute a 15 table upon which the sheet of paper P is supported during transit. A pair of clamps 23 and 24 envelop opposite ends of the rod 21 and are bound to the same through the medium of bolts 25 and nuts 26. This connection is best shown in Fig. II. The upper 20 clamps 23 are longer than the others and extend some distance beyond. Such added extensions of the clamps 23 I have designated as 27. Supported upon these extensions and 25 extending across from one to the other is the electrical heater which corresponds to that of my earlier application, filed November 11, 1919 Serial No. 387,273. It includes a channel support 28 secured as by rivets 29 to the 30 extensions 27 as shown in Figure III. Disposed in the support 28 are a pair of superimposed insulating plates 30 each provided with a series of channels 31 occupied by the resistance coils 32. The latter are caused to 35 glow and radiate heat.

Supported in any suitable manner, in this case with rivets 33 is a bent guard 34 including a downwardly extending end 35 disposed in a substantially upright position just 40 ahead of the heater with reference to the direction of movement of the paper sheet P thereover. The portion 35 is provided above the heater with a series of perforations 36 which may be seen in Figures II and III. 45 The purpose of such apertures is to counteract the retardation of the paper sheet which is passing over it by eliminating the back pull and hesitation due to a suction effect. The other end 37 of the guard 34 slopes 50 downwardly in a direction away from the heater as is clearly shown in both Figures I and III.

The sticks 22, as is illustrated in Figure II, may be variously spaced apart to suit the 55 requirements of the particular job. The determining factor in spacing the sticks 22 is not always the same as the factor which should determine the spacing of stop fingers, and it is accordingly desirable to have the 60 adjustment accomplished. A rod 38 carries a series of brackets 39 adapted to be rotatably fixed by means of set screws 40. The brackets 39 in turn carry the stop fingers 41 which are automatically lifted and depressed 65 in a manner well known to the art whenever

the rod 38 is oscillated. According to my invention the stop fingers 41 are permitted to rest upon the guard 34. In Figure II it will be observed that I provide wires 42 diverging from the sticks 22 and terminating 70 above the guard 34 upon which their free ends may rest. The purpose of the wires 42 is to avoid sagging of the paper sheet or entanglement of any of its edges.

I claim:—

1. A sheet delivery device comprising a conveyor carrying an elongated perforate support extending across a major portion of the delivery end thereof. 75
2. A sheet delivery device comprising a sheet conveyor, a guard mounted ahead with reference to the direction of movement of a sheet upon said conveyor, and a flaring support at the point of meeting of said conveyor and guard. 80
3. A sheet delivery device comprising a sheet conveyor, a guard mounted ahead with reference to the direction of movement imparted to a sheet by said conveyor and supports extending obliquely between said conveyor and guard. 85
4. A device of the character described comprising a sheet conveyor of an elongated perforate member disposed adjacent thereto extending for a considerable distance across 90 it and having a portion thereof below the path of travel of a sheet whereby to counteract retardation of the sheet by elimination of a suction effect. 95
5. A device of the character described comprising a conveyor to move printed sheets of a continuous perforate guard extending in a direction across and disposed beyond the delivery end of said conveyor with reference to the direction of travel of 100 said sheets and adapted to be traversed by said sheets. 105
6. A device of the character described comprising a conveyor over which a printed sheet is to pass, of a guard disposed adjacent 110 to said conveyor and having a portion thereof below the intended path of travel of said sheet, said guard being elevated with respect to the plan of said conveyor. 115
7. A device of the character described comprising a sheet conveyor of a perforate guard disposed ahead of the approached end of said conveyor, said guard extending across from one side of said conveyor to the other and having a portion thereof elevated 120 with respect to the plane of travel of, but adapted to be traversed by said sheets. 125
8. A device of the character described comprising a conveyor over which printed material is to pass, of an elongated guard 130 extending across and disposed with a portion thereof below the path of travel of said material and perforated for the purpose specified.
9. A device of the character described 130

comprising a conveyor over which printed material is to pass, of a guard projecting upwardly above said conveyor and at that end of it which is last traversed by said material, said guard having a portion thereof disposed below the path of travel of said material and provided with an aperture directed substantially along the path of movement of said material.

10 10. A device of the character described comprising a conveyor over which printed sheets are to pass, of a guard having a perforated area projecting above said conveyor, said guard having a portion thereof disposed below the path of travel of said sheets.

11. A device of the character described comprising a carriage including adjustable sticks and stop fingers adapted to swing relative to the plane of said sticks, and a perforate support extending across from one side and the other and between the delivery ends of all of said sticks and fingers.

12. A device of the character described comprising a printed sheet conveying carriage including fly sticks and stop fingers adapted to swing relative to said sticks and a support extending laterally in a direction across the path of movement of said conveyed sheets and located between said heater and the delivery ends of said sticks and fingers whereby to support the sheet at the moment of its delivery from said carriage.

13. A device of the character described comprising adjustable sticks, stop fingers 35 and a support extending between the delivery ends of said sticks and fingers adapted to sustain a moving sheet irrespective of the relative position of said sticks and fingers.

14. A device of the character described comprising a printed sheet conveying carriage, stop fingers adapted to swing relative thereto and a delivery guard both extending laterally in a direction across the path of 45 movement of said conveyed sheets and below said fingers, said guard being located above said fingers.

15. A device of the character described comprising a sheet conveying carriage, 50 sticks thereon, a guard mounted across the ends of said sticks, and a flaring support at the point of meeting of some of said sticks and guards.

16. A device of the character described comprising a sheet conveying carriage, sticks thereon, a guard mounted across the ends of said sticks, and supports extending obliquely between said sticks and guard.

Signed by me, this 23rd day of 60 September, 1921.

JAMES E. DOYLE.
